UNITED STATES PATENT OFFICE.

SAMUEL FREUND-BALLA, OF LOS ANGELES, CALIFORNIA.

DESIGN FOR A MEDAL.

No. 38,681.

Specification for Design.

Patented June 25, 1907.

Application filed May 28, 1907. Serial No. 376,214. Term of patent 14 years.

To all whom it may concern:

Be it known that I, SAMUEL FREUND-BALLA, a subject of the Emperor of Austria, residing at Los Angeles, in the county of Los Angeles and State of California, have invented a new, original, and ornamental Design for Medals, of which the following is a specification, reference being had to the accompanying drawings, forming part thereof.

Figure 1 is a plan view of one side of the medal. Fig. 2 is a plan view of the other side thereof.

I claim:

The ornamental design for a medal, as shown.

SAMUEL FREUND-BALLA.
